APPARATUS FOR MAKING SHOE SOLES

William J. De Witt and Erle Floyd Beers, Auburn,
N. Y., assignors to Dun Deer Sandals, Inc.,
Auburn, N. Y., a corporation of Delaware

Application April 10, 1933, Serial No. 665,296

5 Claims. (Cl. 164—33)

This invention relates to an improvement in apparatus for making shoe soles and is a further development of the invention disclosed in Patent No. 1,843,753 dated February 2, 1932, and has for its primary object to provide apparatus for blanking and preparing shoe soles for assembly with the uppers thereof.

In the drawing:

Fig. 1 is a side elevation of a press by which the soles are blanked out from a sheet of material;

Fig. 2 is an enlarged front elevation of the bed portion of such press;

Fig. 3 is a plan view of the blanking die;

Fig. 4 is an enlarged sectional view taken along the line 4—4 of Fig. 3; and

Fig. 5 is a sectional view of an element of the press.

The press 20 comprises a bolster 21 and a ram 22. The ram is raised and lowered in any well known manner by the shaft 23 having a driving pulley 24 mounted thereon. Supported upon the arms of the bolster 21 is a blanking die 25 comprising a bed plate 26 and a flange 27 projecting upwardly from the plate. The flange 27 is continuous and of a contour substantially similar to that of the sole to be blanked or dinked from the leather or other material. Enclosed by the flange 27 is a base plate 28 secured to the bed plate 26 by screws 29 and further held against relative movement over the bed plate by dowels 30. Mounted on and projecting upwardly from the base plate are slitting and slotting knives 31 and perforating knives 32. The knives shown only in Fig. 4 form no part of the present invention and may be omitted or constructed and arranged, in any suitable manner as shown, for example, in the above mentioned patent. Surrounding the base plate 28 is a continuous shearing knife 33 held in contact with the edge of the base plate by set screws 34.

A stripper plate 35 normally rests upon the base plate 28 and is free to reciprocate within the shearing knife 33 toward and away from the base plate. Freely reciprocable in holes 36 through the base plate 28 and bed plate 26 are rods 37 mounted at their lower ends upon a platen 38. The upper ends of the rods contact with the stripper plate and are preferably secured thereto. Posts 39 secured at their upper ends to the arms of the bolster 21 support at their lower ends a unit 40 comprising an upper plate 41 and a lower plate 42. The plates 41 and 42 are expanded intermediate their ends to form a chamber divided, by a diaphragm 44, clamped between the plates 41 and

42, into an upper compartment 45 and a lower compartment 46. Resting upon the diaphragm 44 in the upper compartment 45 is a plunger 47 the stem 48 of which passes through an opening 49 in the plate 41. The stem 48 terminates at 5 its upper end in a block 50 on which the platen 38 rests. The rods 39 pass through openings in the ends of the platen 38 and thus position it upon the block 50. Air is supplied to the compartment 46 through a hose 51 from any desired 10 source. As here shown a slide valve unit 52 of the well known type controls the supply of air. The air is conducted from the source, not shown, through a pipe 53 to the valve unit 52 and from the unit to the compartment 46 through the hose 15 51. The operation of the valve unit is controlled by a sliding piston 54 which is reciprocated by a link 55 actuated by a cam 56 on the shaft 23. The link 55 depends from a lever 57 pivoted at one end upon an anchor 58 and provided at the other 20 end with a roller which travels in a cam path 59. Through the mechanism thus described the stripper plate 35 is actuated to remove the cut sole from the die plate as will appear from the following description of the operation of the ma- 25 chine.

The ram 22 forces the sheet of material against the knives of the blanking die and the cut sole rests upon the stripper plate 35. As the ram 22 is raised the cam 56 causes the link 55 to descend 30 shifting the piston 54 and allowing air to pass through the unit 52 and hose 51 into compartment 46. The pressure of the air acts upon the diaphragm causing it to raise the plunger 47 and through the block 50, the platen 38 and rods 37 35 40 to actuate the stripper plate 35 thus ejecting the cut sole from the die. As the shaft continues to rotate the parts again resume the positions shown in the drawing and the operation thus described is repeated.

While one such embodiment of the invention has been shown and described it will be understood that the invention is not limited thereto and that other embodiments may be made without departing from the spirit and scope of the 45 invention as set forth in the following claims.

We claim:

1. Apparatus for making shoe soles and preparing them for assembly with shoe uppers including a press for blanking shoe soles comprising 50 a bolster, a ram, a blanking die supported upon the bolster, said die including a base plate, a shearing knife surrounding said base plate and by which the edges of the soles are formed, and a stripper plate enclosed by said knife, means 55

for moving said ram toward and away from said die and stripper plate, actuating mechanism operated by said means for causing the stripper plate to remove the soles from the die as the ram is moved away from the die, said mechanism including a plunger by which the stripper plate is raised pneumatic means for actuating said plunger, and a valve tripped by the ram as it moves away from the die for causing said pneumatic means so to act.

5. Apparatus for making shoe soles and preparing them for assembly with shoe uppers including a press for blanking shoe soles comprising a bolster, a ram, a blanking die supported upon the bolster, said die including a base plate, a shearing knife surrounding said base plate and by which the edges of the soles are formed, and 10 a stripper plate enclosed by said knife, means for moving said ram toward and away from said die and stripper plate, actuating mechanism operated by said means for causing the stripper plate to remove the soles from the die as the ram is moved away from the die, said mechanism including a plunger by which the stripper plate is raised, a chamber, a diaphragm which divides the chamber into two compartments, one end of the plunger entering one compartment and resting upon the diaphragm, and a slide valve operated by the ram moving means to admit air 15 under pressure into the other compartment of the chamber whereby the diaphragm causes the plunger to raise the stripper plate.

15. Apparatus for making shoe soles and preparing them for assembly with shoe uppers including a press for blanking shoe soles comprising a bolster, a ram, a blanking die supported upon the bolster, said die including a base plate, a shearing knife surrounding said base plate and by which the edges of the soles are formed, and 20 a stripper plate enclosed by said knife, means for moving said ram toward and away from said die and stripper plate, actuating mechanism operated by said means for causing the stripper plate to remove the soles from the die as the ram is moved away from the die, said mechanism including a platen, rods carried thereby in contact with the stripper plate, a plunger on which said platen rests, a diaphragm supporting said plunger and a valve actuated by the ram moving 25 means for permitting air to act upon said diaphragm which causes the plunger to raise the stripper plate through the platen and rods.

20. Apparatus for making shoe soles and preparing them for assembly with shoe uppers including a press for blanking shoe soles comprising a bolster, a ram, a blanking die supported upon the bolster, said die including a base plate, a shearing knife surrounding said base plate and by which the edges of the soles are formed, and 25 a stripper plate enclosed by said knife, means for moving said ram toward and away from said die and stripper plate, actuating mechanism operated by said means for causing the stripper plate to remove the soles from the die as the ram is moved away from the die, said mechanism including a platen, rods carried thereby in contact with the bottom of the stripper plate, a plunger on which said platen rests, a chamber, a diaphragm which divides the chamber into 30 two compartments, one end of the plunger entering one compartment and resting upon the diaphragm and a slide valve operated by the ram moving means to admit air under pressure into the other compartment whereby the diaphragm causes the plunger to raise the stripper plate through the platen and rods.

rods, said stripper plate, and a valve tripped by the ram as it moves away from the die for causing said pneumatic means so to act.

4. Apparatus for making shoe soles and preparing them for assembly with shoe uppers including a press for blanking shoe soles comprising a bolster, a ram, a blanking die supported upon the bolster, said die including a base plate, a shearing knife surrounding said base plate and by which the edges of the soles are formed, and 10 a stripper plate enclosed by said knife, means for moving said ram toward and away from said die and stripper plate, actuating mechanism operated by said means for causing the stripper plate to remove the soles from the die as the ram is moved away from the die, said mechanism including a platen, rods carried thereby in contact with the stripper plate, a plunger on which said platen rests, a diaphragm supporting said plunger and a valve actuated by the ram moving 15 means for permitting air to act upon said diaphragm which causes the plunger to raise the stripper plate through the platen and rods.

5. Apparatus for making shoe soles and preparing them for assembly with shoe uppers including a press for blanking shoe soles comprising a bolster, a ram, a blanking die supported upon the bolster, said die including a base plate, a shearing knife surrounding said base plate and by which the edges of the soles are formed, and 20 a stripper plate enclosed by said knife, means for moving said ram toward and away from said die and stripper plate, actuating mechanism operated by said means for causing the stripper plate to remove the soles from the die as the ram is moved away from the die, said mechanism including a platen, rods carried thereby in contact with the bottom of the stripper plate, a plunger on which said platen rests, a chamber, a diaphragm which divides the chamber into 25 two compartments, one end of the plunger entering one compartment and resting upon the diaphragm and a slide valve operated by the ram moving means to admit air under pressure into the other compartment whereby the diaphragm causes the plunger to raise the stripper plate through the platen and rods.
